SHARPENER DEVICE FOR BLADES OF SLICING AND CUTTING MACHINES

Xan B. K. Green, New Paltz, and Harry Preble, Jr., Cross River, N. Y., assignors to General Slicing Machine Co., Inc., Walden, N. Y., a corporation of New York

Application June 18, 1953, Serial No. 362,559

11 Claims. (Cl. 51—248)

The present invention relates to a sharpening device for rotary disc blades and more particularly to the type which is permanently mounted on the machines of which such blades are a part. The sharpening device which is the subject of this invention, is especially adaptable for use in food slicing machines, and such embodiment is herein illustrated to show one application of this invention.

An object of this invention is to provide a novel and improved manually-operated sharpening device of the character mentioned, in which the pressure of the sharpener wheel against the blade is automatically controlled and is independent of the force the operator applies to bring such wheel into sharpening position.

Another object hereof is to provide a sharpening device of the nature set forth, of novel and improved construction, in which the force applied by the operator to shift the sharpening wheel into sharpening position, is not imparted to such wheel to bear pressure against the blade, thus avoiding "burning" of the cutting edge.

A further object of this invention is to provide a novel and improved sharpening device of the class described, which not only sharpens the blade, but also removes any burr resulting on the cutting edge.

Another object hereof is to provide a novel and improved sharpening device for disc blades, applicable for use in food slicing machines.

A further object is to provide a novel and improved disc blade sharpening device of novel and improved construction, which is reasonably cheap to manufacture, easy to use and efficient in carrying out the purposes for which it is designed.

Other objects and advantages will become apparent as this disclosure proceeds.

In the accompanying drawings forming part of this specification, similar characters of reference indicate corresponding parts in all the views.

Fig. 1 is a perspective view of a hand-operated slicing machine which includes a sharpening device embodying the teachings of this invention.

Fig. 2 is an exploded view showing the disc blade and the parts of said machine associated therewith, together with the push-button used to operate the included sharpening device, and also discernable is that part of such device which is used to remove the burrs from the cutting edge after the blade is sharpened.

Fig. 3 is an enlarged fragmentary section taken at lines 3—3 in Fig. 1, showing the sharpening device in its normal rest inactive position.

Fig. 4 is like Fig. 3, but shows the sharpening wheel in operative position.

Fig. 5 is an enlarged view of part of Fig. 4.

In the drawings, the numeral 15 indicates generally a well known food slicing machine having a rotatably mounted disc blade 16 on the housing 17. Said blade, in the embodiment illustrated, carries fixed thereon a gear 18 for engagement with the gear 19 on the shaft 20 which is driven by the crank handle 21. The numeral 22 denotes a plate member serving as a guard for the

2

blade 16, and same is secured to the housing member 17 by means of a screw 23. The assembly and operation of such machine is well known in the machine art, and therefore needs no further explanation.

5 At the top of the housing member 17, through its flange 24, is slidably mounted the shank 25, for longitudinal movement along a line parallel to the face of the disc blade 16 and spaced therefrom. The upper end of said shank, which is exterior the housing 17, carries a head to serve as a push-button. The lower end of said shank, which is interior said housing, is headed. The said push-button is denoted by the numeral 27, while the said lower head is indicated at 28. Said shank 25 carries a freely rotatable abrasive sharpening wheel 29, which is also free for sliding movement along said shank. Said sharpening wheel is of frusto-conical shape and is positioned inverted; its slope corresponding to the bevel 16' of the cutting edge of the blade 16. When the sharpening wheel 29 is lowered, its conical surface contacts the bevel edge 16' of the blade. In normal rest position, the blade and said wheel are out of contact.

The extent of the possible movement of the shank 25, is greater than the distance necessary for the sharpener wheel 29 to travel to contact the blade 16. Said shank 25 carries the compression spring 30 between the button 27 and the flange 24, and also said shank carries another compression spring 31 between wheel 29 and said flange 24. The spring 31 is always in stressed condition. The spring 30 is so much stronger than the spring 31, that when there is no pressure on the pressed-on button 27, the shank 25 will rise to normal rest position, carrying the sharpener wheel 29 out of contact from the blade 16, and spring 31 will become further stressed. This spring 31 is so designed, that when the sharpener wheel 29 is in contact with the blade 16, the pressure imparted by said spring 31 shall be proper to effect good sharpening action by the wheel 29, and such action shall not be in any excess to cause undue pressure against the blade. This avoids "burning" of the cutting edge.

40 It is to be specially noted that it is only the action of spring 31 which determines the pressure between sharpener wheel and blade. This is because the sharpener wheel 29 is free for sliding movement along the shank. All pressure applied to the shank 25 by the operator pressing on the button 27, and regardless as to its extent in force, is never imparted to the sharpener wheel 29. The spring 30 only serves to restore the components to their normal rest position as shown in Fig. 3.

50 The plate 22 is of sheet metal having resilient quality, and is formed with an indentation 32 forming a protuberance 33 on its outer surface. Within said indentation, said plate has secured thereon a piece of sharpener stone 34. The blade 16 is between said stone and the sharpener wheel 29. When the operator presses on the region 33 of the plate 22, said stone 34 is brought into contact with the back surface of the blade 16, across the rim edge of said blade in the plane of the blade. Upon release of hold on the region 33, the plate 22 will spring back to normal rest position where said stone piece 34 assumes its normal rest position, spaced from the blade. The action of this stone is to remove any burr on the blade edge which might be caused when the sharpener wheel 29 acts on the blade.

65 To sharpen the blade, it is rotated and button 27 is pressed on to move as far as it will go, thereby stressing the spring 30. The sharpener wheel 29 will contact the rotating blade 16 and sharpen its edge 16'. The operator now releases hold on the button 27, whereupon spring 30 will act and restore shank 25 to its outward normal rest position. The head 28 will carry the sharpener wheel 29 away from the blade and the parts will be in their

normal rest position as in Fig. 1 again. Now, while the blade is rotated, the operator will press on region 33 of plate 22, thereby bringing the stone piece 34 into contact with the blade 16 to remove any burr from the blade edge. Upon release of pressure on the plate region 33, said plate will spring back effecting separation of the stone piece 34 from the blade.

This invention is capable of numerous forms and various applications without departing from the essential features herein disclosed. It is therefore intended and desired that the embodiment shown herein be deemed illustrative and not restrictive, and that the patent shall cover all patentable novelty herein set forth; reference being had to the following claims rather than to the specific description herein to indicate the scope of this invention.

We claim:

1. In combination with a frame and a bevel-edged disc blade rotatably mounted thereon, of a blade sharpening means comprising a shank longitudinally slidably mounted on a frame part which is spaced from said blade; the ends of said shank extending into space, a blade-sharpening member slidably carried on one end of the shank; said shank being positioned whereby on longitudinal movement thereof in one direction, said sharpening member will contact the bevelled edge of the blade; said shank having a protuberance on said end to maintain said sharpening member and shank in associated relation, a first spring means acting on said sharpening member to urge same towards the bevelled edge of said blade, a second spring means acting on the said shank to urge same to move so that said protuberance shall carry said sharpening member away from said blade edge; said first spring means exerting sufficient force on the sharpening member when the latter and the blade are in contact, to effect sharpening of said blade when said blade is revolved; said shank being capable of movement in the mentioned direction to such extent that said protuberance will not stop movement of the sharpening member along the shank when said member and the blade are in contact; the first spring means being constantly in stressed condition and the second spring means in normal rest condition, holding the shank in such position that the protuberance on said shank holds the sharpening member out of contact with the blade and stresses the first spring.

2. The combination as defined in claim 1, wherein the blade-sharpener member is a wheel rotatably carried on the shank.

3. The combination as defined in claim 1, wherein the blade-sharpener member is a wheel rotatably mounted on the shank in co-axial relation therewith.

4. The combination as defined in claim 1, wherein the shank is positioned angularly to the axis of the disc blade and wherein the sharpening member is a wheel of frustoconical shape, rotatably mounted on the shank in co-axial relation therewith; the curved surface of said wheel being the one which contacts the beveled edge of the disc blade when said shank is moved towards the axis of the blade.

5. The combination as defined in claim 1, wherein each spring means consists of a coil spring positioned about the shank.

6. The combination as defined in claim 1, wherein each spring means consists of a compression coil spring positioned about the shank.

7. The combination as defined in claim 1, including an element having resilient quality mounted on the frame and positioned spaced from the disc blade and substantially parallel thereto on the side of said blade opposite that having the bevelled edge, and a second blade-sharpening member mounted on said resilient element spaced from the said blade when said element is in normal rest position; said resilient element being adapted to be manually shifted whereby the second sharpening member contacts the unbevelled edge of the blade to remove any burr on said edge upon rotation of said blade.

8. The combination as defined in claim 7, wherein the first blade-sharpener member is a wheel rotatably mounted on the shank and the second sharpening member for removing the burrs on the edge of the blade is fixedly secured on the mentioned resilient element.

9. The combination as defined in claim 7, wherein the frame and disc blade are of a food slicing machine, and wherein the element of resilient quality is part of the frame shielding the blade.

10. In combination with a frame, a bevel-edged disc blade and a sharpening means for the bevelled edge of said blade, both mounted on the frame; a part of the frame being positioned spaced from said blade, substantially parallel thereto on the side of said blade opposite that having the bevelled edge and of an extent whereby it serves to shield the major portion of said side of the blade which is opposite that having the bevelled edge; a portion of said part of the frame having resilient quality and a blade sharpening member mounted on said resilient portion and spaced from said blade when said portion is in normal rest position; said resilient portion being adapted to be manually shifted whereby said sharpening member contacts the edge of the blade surface adjacent said portion to remove any burr on said edge, upon rotation of said blade.

11. The combination as defined in claim 10, wherein the sharpening member for removing the burrs is a body fixedly secured on the mentioned resilient portion.
